LOUDEN A. McCOURBIE AND CHARLES F. RAYDURE, OF PHILADELPHIA,
PENNSYLVANIA.

ELECTRIC MOTOR.

943,155.

Specification of Letters Patent. Patented Dec. 14, 1909.

Application filed April 29, 1909. Serial No. 493,061.

To all whom it may concern:

Be it known that we, LOUDEN A. McCOURBIE and CHARLES F. RAYDURE, both citizens of the United States, residing at the city 5 of Philadelphia, in the county of Philadelphia and State of Pennsylvania, have jointly invented certain new and useful Improvements in Electric Motors, of which the following is a specification.

10 Heretofore difficulty has been experienced in maintaining the commutator faces of electric-motors free from rib formations or projections, which cause arc drawing and sparking, and it is highly desirable to prevent such formations, which is the principal object of our present invention.

Our present invention will be more fully understood from the following description in connection with the accompanying drawings forming part hereof, in which—

20 Figure 1, is a vertical sectional view through a casing or housing for an electric motor having carbon or other brushes adjustably suspended from brackets in such 25 relation with respect to the commutator as to not only insure spring contact of the brushes therewith but to also prevent rib formations or projections being formed around the commutator faces, the same embodying main features of our said invention.

25 Fig. 2, is a top or plan view, showing the arrangement of a plurality of carbon-brushes on each side of the commutator and preferably set at 90° apart, as is usual in car 30 motors, and with means for maintaining each in contact with the said commutator. Fig. 3, is a rear elevational view of means for holding the carbon-brushes under spring tension from the brush-holders, for use in

35 contact with the commutator. Fig. 4, is a vertical central sectional view through one of the brush-holders provided with a plurality of carbon-brushes, one being of a different size from the other in each set, and

40 showing also in detail the arrangement of the spring tension device to maintain the said plurality brushes of each of said holders in direct surface contact with the commutator; and Fig. 5, is a diagrammatic plan 45 view of a commutator laid out flat and the different size plurality brushes of each of said holders, the brushes of the respective holders being in such a position as to occupy 50 a staggered relationship in respect to one an-

other in contact with the commutator, the 55 said view disclosing as such, essentially, main features of our said invention.

Referring to the drawings A, is a metal casing of suitable form, for housing the electric-motor B, having a commutator b, 60 journaled on both sides at b¹, in the casing A, as clearly illustrated in Fig. 2.

C, is a brush-holder recessed at c, on each side of a central rod or support c¹, and provided with journals c², for adjustably supporting the holder in the sleeve d, of a bracket d¹, which is bolted at d², on each side of the commutator to the casing A, as clearly illustrated in Figs. 1 and 2. In the recesses c, on both sides of the central rod 70 or support c¹, of the holder are mounted pivoted tongues c³, having coiled springs c⁴, passing around the bearings of said tongues, with the ends respectively, suitably connected with the holder and tongue. In the front 75 of the holder is provided an oblong slot c⁵, with a partition c⁶, so as to divide the holder into two openings of different size for receiving carbon or other brushes e and e¹. These brushes are held in the slots c⁵, and 80 therefrom in contact with the commutator b, by means of the spring controlled tongues c³, as illustrated in Figs. 1 and 2. These holders with their different size carbon-brushes e and e¹ on both sides of the commutator b, set as shown at an angle of 90° thereto, occupy staggered relationship to one another in contact with the commutator as illustrated in Fig. 5, whereby in the operation of the commutator, with the brushes so 85 arranged is prevented rib and other formations on the commutator and thus the usefulness of the commutator is prolonged beyond present day uses of such as well as 90 arc-ing and sparking between the commutator and the brushes of the same avoided.

Having thus described the nature and objects of our invention, what we claim as new and desire to secure by Letters Patent is:—

100 In an electric-motor, a commutator, brush-holders, each consisting of a hollow casting provided with a transverse partition having long and short slots therein; the slots of successive holders in relative positions alternating, brushes fitting said slots, each of the 105 holders provided with a support, tongues on both sides of said support and coiled springs mounted on bearings of said tongues and

having the ends respectively connected with
said holders and tongues so as to maintain
under spring tension said brushes in con-
tact with the commutator to prevent rib and
other formations as well as sparking or arc
drawing between said commutator and
brushes thereof.

In witness whereof, we have hereunto set

our signatures in the presence of the two
subscribing witnesses.

LOUDEN A. McCOURBIE.
CHARLES F. RAYDURE.
